UNITED STATES PATENT OFFICE.

DANIEL FOGARTY, OF OTTAWA, ONTARIO, CANADA.

SEPARATING-TANK FOR VACUUM CLEANING APPARATUS.

940,142.

Specification of Letters Patent. Patented Nov. 16, 1909.

Application filed July 11, 1908. Serial No. 443,128.

To all whom it may concern:

Be it known that I, DANIEL FOGARTY, of the city of Ottawa, in the county of Carleton, Province of Ontario, Canada, have invented certain new and useful Improvements in Separating-Tanks for Vacuum Cleaning Apparatus, of which the following is a specification.

My invention relates to improvements in separating tanks for vacuum cleaning apparatus, and the objects of my invention are to provide certain improvements in detail, as given hereinafter in the specification and claim.

15 In the drawings,—Figure 1 is a side view of the apparatus partly in section. Fig. 2 is an enlarged sectional detail of the head of the vacuum separating tank.

20 In the drawings like letters of reference indicate corresponding parts in each figure.

A is the dust collecting chamber into which extends the screening chamber B which is cylindrical and provided with a head a, having an aperture b therein, which is internally screw-threaded and engaged by an externally screw-threaded cylindrical member c, the top of which is engaged by a ring d, which supports the screening chamber within the dust collecting chamber. A hand-hole w is provided in the dust collecting chamber for the removal of dirt. The screening chamber may be formed of any material pervious to air, but impervious to dust. I prefer to form it of a layer of coarse screening netting covered by a layer of fine brass wire cloth, in turn covered with muslin or other cloth. The coarse netting, which may be about three-eighths of an inch mesh, serves to hold the fine wire cloth, which may be about 40 sixty threads to the inch, in shape.

C is a suitable form of pump, preferably double-acting, and having pipes e, f, g and h extending from the exhausting ports thereof, to a single pipe i, which connects with a 45 cylindrical member j, which has screw-threaded engagement with a connecting member k, the lower end of which has screw-threaded engagement with a ring l which is connected through the medium of a packing ring m to the cylindrical member c. The

50 pump discharges through a conductor n, the extremity of which is provided with a valve o and this conductor is connected by a pipe p with the pipe i, a valve q being inserted in the pipe p and a similar valve r in the pipe i 55 between the point of connection of the pipe p and that of the four pipes e, f, g, and h.

The dust collecting chamber is placed in communication with the vacuum nozzle, by means of a suitable conducting pipe s which 60 extends therein. Below the valve r a T-coupling t is secured having a conducting pipe u adapted to communicate with the air but controlled by a valve v.

In ordinary operation, the valves o and r 65 will be opened, and the valves q and v closed. The pump being operated in the ordinary manner, will create a vacuum in the screening chamber to suck the air therein, the dust drawn out of the carpet, or other article being cleaned, being separated by the screen and remaining in the dust collecting chamber.

70 It will be observed that the air laden with dust discharges downwardly into the dust collecting chamber and part will settle on the bottom, while the air is drawn upward into the vacuum separating chamber.

If through the continuous operation the screen should become covered with dust and 75 operates unsatisfactorily, the valves o and r are closed, and the valves q and v are opened, and the air current produced by the pump reversed in operation. This will force air through the conductors n, p and i into the 80 vacuum chamber and through the screen, cleaning the same, the air for this operation being drawn in through the conducting pipe u and the conducting pipes e, f, g and h.

85 It will thus be seen that I have devised an 90 exceedingly cheap and simple form of screening tank, which embodies all the advantages which it was the object of the invention to attain.

95 What I claim as my invention is:

An improved vacuum separating tank comprising in combination, a vertically extending cylindrical casing having a hand-hole near the bottom for the removal of dirt, and having an internally screw-threaded aper- 1

ture at the top thereof, an externally screw-threaded cylindrical member engaging the aperture, a cylindrical screen extending within the chamber, a ring connecting the screen with the cylindrical member, a vacuum suction pipe connected to said cylindrical member and adapted to exhaust the interior of the chamber, and a small downwardly dis-

charging pipe for the dust laden air extending through the cylindrical member. 16

In witness whereof I have hereunto set my hand in the presence of two witnesses.

DANIEL FOGARTY.
